David S. Williams

ATTORNEY.

UNITED STATES PATENT OFFICE.

GEORGE C. RITTENHOUSE, OF GLENDALE, PENNSYLVANIA.

EXHAUST-HEAD.

No. 903,887.

Specification of Letters Patent.

Patented Nov. 17, 1908.

Application filed April 3, 1908. Serial No. 424,987.

To all whom it may concern:

Be it known that I, GEORGE C. RITTENHOUSE, a citizen of the United States, residing at Glendale, in the county of Montgomery and State of Pennsylvania, have invented certain new and useful Improvements in Exhaust-Heads, of which the following is a specification.

This invention relates to the construction 10 of exhaust-heads, especially of such as are used in connection with highly heated exhaust steam, and in which a large area of cooling surface is essential to reduce the steam to the point of condensation.

15 The object of my invention is to provide a construction of the exhaust-head of especially simple and compact form, which is readily attachable to an exhaust pipe and which will provide for an increased area of cooling surface and a free circulation of atmospheric air in horizontal planes through the exhaust-head as to provide for the expeditious condensation of highly heated steam to relieve the exhaust pipe of back pressure.

20 25 The nature of my improvements will be best understood as described in connection with drawings in which they are illustrated and in which

Figure 1 is a perspective view of an exhaust-head embodying my invention. Fig. 2 represents a vertical section of the device taken on a line 2—2 of Fig. 1. Fig. 3 shows a horizontal section of the same taken on a line 3—3 of Fig. 2, and Fig. 4 is a side elevation of an exhaust-head embodying my invention.

A, indicates the shell of the exhaust-head which is preferably cylindrical in shape and which is furnished with a conical base A¹, 30 fitted with exhaust connections which comprise a fitting A², to receive the exhaust steam pipe and a fitting A³, to receive a drain pipe. The shell A, is provided with openings a, a, etc. to receive the ends of air cooled 40 condensing tubes B, which may be rectangular in cross section as illustrated in Figs. 1, 2 and 3 of the drawings or circular as illustrated in Fig. 4. Several of the tubes B, are centrally connected within the shell and form 45 a group of tubes having a central line of communication within the exhaust-head. Two or more groups or clusters of these air cooled tubes B, are arranged in juxtaposition within the shell A, presenting superposed 50 clusters of tubes horizontally disposed throughout the exhaust-head. The top of

the shell A, is provided with a conical cap C, having a central discharge opening C¹, to receive a perforated pipe C², which as shown in Fig. 2 is interposed between said cap and the uppermost layer of cooling tubes. The pipe C², by reason of its location acts as a final chill to the partially condensed steam as also a screen to arrest and dispose of a portion of the condensed vapor.

60 As illustrated in Fig. 4, a cluster of air cooled condensing tubes B, is arranged about a central drum B¹, which forms a medial line of communication for all of the tubes of the cluster and which may, if desired be in communication with the adjacent drum B¹, of the superposed series, in which case there would be formed a line of communication with all of the tubes of the exhaust-head.

65 In operating the device, the exhaust fluid enters through an exhaust pipe D (indicated by dotted lines) and is carried in the direction of the arrow against a cone or spreader D¹, by which its course is gently diverted causing the fluid to enter the path of the first 70 cluster of air cooled condensing tubes.

75 As the tubes of the superposed clusters or series are staggered or out of alignment the fluid will pursue a zigzag course through the space between the tubes causing the precipitation of much of its vapor as it is met by and impinges upon the numerous tubes which together with shell or casing of the exhaust-head constitutes a broad area of cooling and condensing surface. Impinging upon and 80 reacting from the cap C, the expanded vapor will pass through the perforations in the pipe C² and through the openings C¹ of the cap to the atmosphere.

85 Having described my invention what I claim and desire to secure by Letters Patent is:

1. An exhaust-head comprising an outer shell provided with exhaust connections, a plurality of radially disposed tubes located 100 within the shell and adapted to contain air, and a cap to said shell provided with a centrally located discharge opening.

105 2. An exhaust-head comprising in combination with the outer shell and exhaust connections, a plurality of tubes arranged in a horizontal plane and connected together within the shell, and a cap to said shell and adapted to convey air provided with a centrally disposed discharge opening.

110 3. An exhaust head comprising an outer shell provided with exhaust connections, ra-

dially disposed and centrally connected cooling tubes arranged in superposed layers within the casing forming passages for air, and a cap joined to the shell and provided with 5 a central discharge opening.

4. In combination with the shell of an exhaust head, a plurality of radially disposed and centrally connected cooling tubes arranged in superposed layers within the shell 10 and adapted to contain air, a cap provided with a central discharge opening and a perforated tube adapted to said opening and interposed between the cap and the uppermost layer of cooling tubes.

5. In an exhaust-head, in combination with 15 the exhaust connections and outer shell, a superposed series of radially disposed tubes adapted to contain air arranged within the shell and connected to or forming part of a central casing or hub, a cap provided with a 20 central discharge opening and a perforated tube adapted to said opening within the shell.

In testimony whereof I affix my signature in presence of two witnesses.

GEORGE C. RITTENHOUSE.
